UNITED STATES PATENT OFFICE

ROBERT H. ZSCHAU, OF CINCINNATI, OHIO

VOTING MACHINE

Application filed January 15, 1932. Serial No. 526,833.

My invention relates to voting machinery and has as its object the simplification of mechanisms for this purpose, while at the same time, providing all the necessary safeguards so that improper voting will be impossible.

It is my object to provide a machine which makes marks on ballots, in the particular example shown, the marking being a punch. 10 My mechanism therefore, necessarily includes means for mounting ballot holders, means for moving the ballot holders to a station for making the markings thereon, means for advancing the ballots in the holders so that 15 each mark will come at a different point, means for preventing duplicate voting, means for preventing voting for more than one candidate for an office, and in general, a mechanism which is simple and foolproof and easy 20 to set up and operate.

I accomplish my objects by that certain construction and arrangement of parts of which a typical example will be illustrated and described, and I hereby refer to the appended claims for a statement of the novelty 25 and invention which resides in the illustrated construction and its mechanical equivalents.

In the drawings:

Figure 1 is a vertical section through the 30 machine showing the parts in position just preceding a voting operation.

Figure 2 is a like section, only fragmentary, showing the parts in position after the first voting operation.

35 Figure 3 is a section on the line 3—3 of Fig. 2.

Figure 4 is a top plan view partly broken away, of the machine.

40 Figure 5 is a plan view of one of the ballot holders.

Figure 6 is a side elevation of one of the ballot holders.

Figure 7 is one elevation, and Figure 8 another elevation of the ballot punch.

45 Figure 9 is a plan view of the ballot.

Figure 10 is an end elevation of the actuating slide.

The machine as illustrated, is mounted on a base 1, which can be set on the table of a 50 voting booth. Located centrally of this base

is a threaded socket 2, which mounts a post 3. A collar 4 is mounted on the post 3 and bolted to the collar are bars 5 and 6 which act as the mounting for the fixedly located portions of the mechanism. These bars 5 and 6 are additionally supported on brackets 7 and 8 bolted to the base and the bars respectively. Set over the post is a sleeve 9 having a cap 10, which bears on the top of the post so that the sleeve can be dropped over the post and revolved thereon. There are collars 11 and 12 which are fast on the sleeve 9. The collar 11 serves to mount a cylindrical block 13, which block has vertical slots 14 therein, one slot for each ballot holder. On top of the block is a plate 15 which is provided with slots 16, engaging around screws 17 in the block, so that the plate 15 can be moved with respect to the screws and clamped into position by wing nuts 18 on the screw. 60 The plate has teeth 19 which depending on the position of the plate, either lie over the slots in the block 13, or free the slots so that the ballot holders may be lifted out. 70

Attached to the lower end of the block 13 is the ballot holder table 20, which is braced to the cap 10 by braces 21. The table 20 has a series of posts 22, one for each ballot holder. The ballot holders themselves are in the form of flat thin plates 23, having sleeves 24 at 80 their outer end. As so constructed the holders may be dropped in a place with the sleeve portions over the posts 22, and the inner ends in the slots of the central block.

Resting on the top of the block 10 is a truncated conical shaped cover 25, having a depending flange 26, which rides over a cylindrical casing 27 located on the base. The cover is held removably in place by means of a padlock 28 engaging a lug 29 that passes 85 through the top of the cover. Located on the cover are a series of fingers 30, one for each ballot holder and indicating the position of the ballot holder, which fingers may be used to mount cards containing the name, office and party of the candidate. Mounted on the cylinder 27 is an indicator 31 which marks the point opposite which a ballot holder must be brought in order to make a mark thereon. 90

The cover 25 is manipulated by means of 100

hand grips 25a and through the lug 29 on the cap 10, serves as a driver to move the ballot holders to the station for making a mark by revolving the sleeve 9 and with it the ballot holders.

Prior to describing the mechanical arrangements further, it may be noted that the ballot holders may be arranged so that a certain number of them will be for straight party votes, and then the remaining holders, one for each candidate; that the revoluble cover 25 will contain indications so that the voter can bring to the marking point the ballot of the candidate for whom he wishes to vote, whereupon, he will depress a lever, to rotate the ballot and make a mark by perforating the ballot which he has brought into position, and that by preventing the revolving parts from moving in any but one direction, and providing a lock which will come into operation after one complete rotation, a very simple and convenient voting mechanism is provided.

25   Ballot holders

The ballot holder plates 23 serve to mount pivot studs 32 on which are located large ratchets 33. The ballots as illustrated in Fig. 9, are circular pieces of paper or cards 34 appropriately printed and calibrated at their margin, and on which margin a series of punch marks 35 are to be made. These ballot papers have central holes 36 which are mounted over a collar 37, set on the stud 32. Dished plates 38 slotted at the margin as at 39, to make them resilient, are mounted over the collar 37 and nuts 40 serve to hold these plates 38 against a ballot which is inserted, and rests against the large ratchet 33 with its margin projecting from the ratchet. The collar 37 is held in place by a screw 41 engaging the stud 32.

The result of this structure is that each time the ratchet is advanced one tooth, the ballot itself is revolved one space. On the plates 23 are spring centering pawls 42, which engage the ratchet 33. The plates 23 are slotted near their inner end for passage of two studs 43 and 44. These studs engage in a flat bar 45 having a C shaped lower end 46. On the opposite side of the plate 23 from the bar 45 is mounted the pawl 47, which by gravity engages the ratchet 33 and also a plate 48 which steadies and guides the motion of the bar 45. The slots in the plate 23 for the mounting studs 43 and 44 are so proportioned that pushing up on the end 46 of the bar 45 will advance the pawl to move the ratchet 23 one notch.

66   The holder table 20 is provided with narrow slots 49 which receive the margins 34a of each ballot card, when it is in place in the machine. Secured on the under side of the table 20 are a series of punch mechanisms, one for each ballot card. These punch mecha-

nisms as shown, particularly in Figures 7 and 8, have mounting plates 50 for securing them to the under side of the table, bodies 51 presenting an upwardly open slot 52 to receive the margin of a card projecting through the slot 49 adjacent to which the punch is mounted. The punch die 53 for each punch slides in and out laterally across the slot 52 of the punch, the outer end of the die being secured to a plate 54. This plate 54 has also a pin 55 thereon around which is a spring 56 seated in a dwell 57 in the body 51. The pin 55 is guided in the body. The result of this construction is such that when the plate 54 is thrust inwardly, the punch will operate across the slot 52, and that when the pressure is released the punch will return to its outer position, permitting the ballot card to be repositioned with its margin in the slot 52.

It will be noted that the ballot mounting means now described, is such that ordinary paper, cardboard, or the like, may be used as a ballot, in view of the fact that the margin is guided absolutely flat and is held on both sides in the punching mechanism itself at all times.

The operating mechanism

Mounted on the lower collar 12, which it will be recalled is fixed on the revolving sleeve 9, is a toothed disc 57. Secured on the plate 6 is a stud 58 that mounts a pawl 59, which engages a roller 59a in the teeth of the plate 57 to definitely locate the ballot, and due to the configuration of the teeth prevents rotation of the machine except in the direction of the arrow 60 (Fig. 4), the spring 61 serving to keep the pawl in mesh with the teeth of the plate 57. Mounted on the plate 5 is a bracket 62 which is bifurcated at its upper end as at 63, for pivotally supporting a latch bar 64. This bar 64 rests on the disc 57 in other than a radial position, and mounted near the center of the plate 57 is a stop 65 formed of an angle plate of metal which is in a position at right angles to the inner end of the latch bar 64. The arrangement is such that when the end of the latch bar comes opposite the abutment 65, the rotation of the mechanism is stopped. To release the mechanism for another operation requires the use of a key for swinging the bar 64 upwardly, and a small spring latch 66 is set in the abutment 65, so that when the bar 64 is kicked up over the top of the abutment, it will be held there by the latch 66 until the mechanism has been rotated through a small portion of its path, whereupon the bar 64 will drop on to the disc 57, ready to stop the rotation of the machine after it has completed another complete revolution. The bar 64 is kicked up by means of the key in the control of the election officials in charge of the booth. On the bracket 62 is a rod 67 which projects outwardly to an available point, and the key

consists of a sleeve 68 which slides over the rod having a fork 69, which engages the inner end of the latch bar 64, and kicks the said bar upwardly past spring latch 66, whereupon the 5 key can be immediately withdrawn.

The mechanism for operating the punch and the advancing pawl elements of the machine consists of a slide 70 having depending flanges 71, and held by a bottom plate 71a, 10 to slide on a plate 72 supported on a post 22a, on the mounting plate 5. On the slide 70 is a vertically extending cam 73, which engages the lower end 46 of the pawl operating bar 45, and moves it upwardly advancing the 15 ratchet 33 one tooth. Also arranged on the slide 70 is a slanting finger 74, which will engage the plate 54 of the punch and move it inwardly as the slide is operated. The 20 slide is shown in its inner position in Figure 1, and its advanced position in Figure 2, and it will be observed that the first operation is to move upwardly the pawl operator, advancing the ballot, and the second operation is to move inwardly the punch, marking the 25 ballot in its newly advanced area. The pawl operator will stay in its upper position as shown in Figure 2 until it is positively lowered from that position for a purpose which will be described. The means for operating the slide consists of a handle 75 pivoted at 76, 30 in a bracket depending from the mounting plate 5; the inner end of the handle is toothed as at 77 for engagement with a full throw pawl 78. Also mounted on the handle is a cam 79, on which rests a pin 80, which pin passes through a hole in the plate 5 and carries a plunger 81, which plunger moves upwardly through a hole 82 in a disc 20, there being one hole for each ballot holder. 35 The conformation of the plunger 81 will be such that it acts as a positive locating device for the disc 20. It will also be observed that if the plunger 81 cannot rise through the hole, the operation of the handle is blocked.

Secured fast to the handle is an arm 83 which is connected to a link 84, said link being pivotally connected to the slide. The advanced position of the pawl for the ratchet of any one ballot is maintained to limit each voter to one mark thereon, and this can be used as an indication of whether or not the ballot holder has been operated. Accordingly the pawl is held in its upper position by friction between the plate 23 and the slide bar 45 which moves the pawl until it is positively pulled down. The mechanism for pulling down the pawl and its operator, as illustrated in Figure 1, is diametrically opposite the main operating device, but this is for convenience in illustration, as it will be preferable to have this clearing device located adjacent to the locking bar 64, to the end that up until the last operation of the machine at the end of one complete rotation, it will be 65 possible for the election official to observe

at the request of a voter, by unlocking and removing the cover 25, what ballot holders have been operated. The device itself consists of a plate 85 mounted on a supporting post 86, and having a cam finger 87, that 70 engages in the C shaped end 46 of the pawl operating bar, and as the machine is revolved, pulls it down.

It is obvious that some other type of indicator could be used, and it is also obvious that if it were desired to make it impossible for the election official to know what ballot holders had been operated, to locate the device 87 on the opposite side of the locked position of the machine, so as to clear each 80 pawl holder the moment the ballot was moved from the marking station.

Where candidates for the same office are grouped together, it is advantageous to prevent the voter from voting for both candidates, or for more than one candidate, and to that end I provide the disc 20 with suitable holes 88, in which inhibiting plates may be mounted. One of these plates is illustrated in Figure 4, at 89. In Figure 4, the plate 89 90 is in position so that it will not block the rise of the centering plunger 81, which it will be recalled, must rise through a hole 82 in a disc 20, in order that the operating handle 95 may be moved. However, when the plunger 81 rises, its end is shaped so as to strike the one end of the plate 89 and rock it to the position shown in dotted lines at 89a. This will serve to bring the other end of the plate 89 100 in a position to block the next adjacent hole 82 in a disc 20, thereby preventing a voting operation with respect to the ballot held in the holder at its next station. The plate 89 could be configured to close more than one adjacent hole 82. To return the plate 89 to 105 normal position, a cam plate 90 is secured to the cylindrical casing and projects up into the path of the plate 89.

It is believed that the operation of the machine will now be clear without further description, and that from the point of view of the essential features involved, a wide variety of equivalent mechanical devices could be utilized to set up the various features of the operation of the machine, and provide the 110 necessary interlocks and operation controls.

Having thus described my invention, what I claim as new and desire to secure by Letters Patent is:—

1. In a voting machine, a plurality of movable ballots, means for marking said ballots, operating means for said marking means, means for causing movement of selected ones of said ballots into position whereby said operating means may actuate said marking means to mark on the ballot, and means for causing movement of said ballots to present successive portions thereof to the marking means.

2. In a voting machine, a plurality of mov-

120

115

125

130

able ballots, means for marking said ballots, operating means for said marking means, means for causing movement of selected ones of said ballots into position whereby said operating means may actuate said marking means to mark on the ballot and means operated by said operating means preliminary to its actuation of said marking means for causing movement of said ballots to present successive portions thereof to the marking means.

3. In a voting machine, a plurality of movable ballots, means for marking said ballots, operating means for said marking means, means for causing movement of selected ones of said ballots into position whereby said operating means may actuate said marking means to mark on the ballot, a plurality of means operated by said operating means preliminary to its actuation of said marking means, one for causing movement of said ballots to present successive portions thereof to the marking means and the other for fixing the ballot in its said position.

4. In a voting machine, a plurality of movable ballots, marking means for each ballot, moving therewith, a stationed operating means to operate said marking means, means for causing movement of selected ones of said ballots and their respective marking means into position whereby said operating means may actuate said marking means to mark on the ballot, and means for causing movement of said ballots to present successive portions thereof to the marking means.

5. In a voting machine a rotary ballot table, having means for mounting a series of ballot holders removably thereon, ballot holders mounted on said means, a cover moving with the table and removable to make the ballot holders available, marking means for ballots carried on the table, and stationed means for actuating said marking means.

6. In a voting machine a rotary ballot table, having means for mounting a series of ballot holders removably thereon, ballot holders mounted on said means, perforating means for ballots carried on the table, and stationed means for actuating said perforating means, said perforating means for the ballot comprising a slotted member in the slot of which the ballots are located so as to support the portion being perforated.

7. In a voting machine a rotary ballot table, having means for mounting a series of ballot holders removably thereon, ballot holders mounted on said means, perforating means for ballots carried on the table, stationed means for actuating said perforating means, said ballots being circular cards, means for operating the perforating means, and means located on the ballot holders and operated by said operating means for moving the cards in a rotary direction irreversibly, preceding

each marking operation and as a necessary incident thereto.

8. In a voting machine a rotary ballot table, having means for mounting a series of ballot holders removably thereon, ballot holders mounted on said means, perforating means for ballots carried on the table, stationed means for actuating said perforating means, said perforating means for the ballot comprising a slotted member in the slot of which the ballots are located so as to support the portion being perforated, said ballots being circular cards, means for operating the perforating means, and means located on the ballot holders and operated by said operating means for moving the cards in a rotary direction irreversibly, accompanying each marking operation and as a necessary incident thereto.

9. In a voting machine, a series of ballots arranged along a plane at an angle to their faces, an operating device, said ballots and said operating device being relatively movable in said plane to juxtapose the operating device and successive ballots, and the operating device and each juxtaposed ballot being relatively movable in a plane along the faces of the ballots, to establish operative relation of the operating device to various portions of each ballot, and means operated by the operating device when in said operative relation, to mark each portion of each ballot.

10. In a voting machine, a series of ballots, marking devices, one for each ballot, and an operating device, said ballots and their marking devices and said operating means being relatively movable to establish operative relation of each marking device to various portions of the respective ballot and to establish operative relation of the operating device to each marking device, whereby the operating device may operate to mark each portion of each ballot.

11. In a voting machine, a series of ballots, an operating device, said ballots and said operating device having relative movement in one plane to establish operative relation of said operating device to each ballot, and each ballot and said operating device also having relative movement in another plane to establish operative relation of said operating device to various portions of each ballot, and means operated by the operating device when in said operative relation, to mark each portion of each ballot.

12. In a voting machine, a series of units, each comprising a marking device and a feeding device to move a ballot to bring various portions of the ballot into position to be marked by said marking device, and a common operating means for all of the marking and feeding devices, said units and said operating device being relatively movable to establish operative relation of said operating

device to the marking and feeding devices of each unit.

13. In a voting machine, a series of ballots, an operating device, said ballots and said operating device having relative movement in one plane to establish operative relation of said operating device to each ballot, and each ballot and said operating device also having relative movement in another plane to establish operative relation of said operating device to various portions of each ballot, a feeding device actuated by the operating device to effect the latter relative movement at each operative relation of the operating device to a ballot, means whereby said feeding device is limited to a single actuation during operative relation of the operating device to each ballot, and means operated by the operating device when in said operative relation, to mark each portion of each ballot.

14. In a voting machine, a rotatable car-

rier limited to rotation in one direction, units removably mounted on said carrier, each comprising a rotatable ballot, feeding means operative to rotate the ballot and a marking device operative to mark successive portions of the ballot set thereat by rotation of the ballot, a stationed operating device at which the units are successively set by rotation of said carrier, adapted to operate the feeding means and marking device of each unit set thereat, a cover concealing the units and preventing access thereto except by said operating device, means to render each feeding means inoperative after a single ballot-portion-feeding operation in each setting thereof, means to restore operativeness of each feeding means upon rotation thereof past each setting thereof, and means locking said carrier against rotation once in each revolution thereof.
